dian.

Application November 13, 1939, Serial No. 304,227
In Great Britain July 19, 1939

6 Claims.

(Cl. 42—6)

This invention relates to automatic or repeating firearms of the kind wherein the box magazine, arranged below the bolt mechanism, can be folded into an out-of-action position and into the forearm of the weapon.

The present invention comprises means for locking the magazine, by means of a folding sleeve, holding the latter, either in its firing position or in its position when folded into the forearm of the weapon, the same means being also adapted for covering that opening in the stock of the weapon, which would else remain open and exposed when the magazine is folded into the forearm of the weapon.

One embodiment of the invention is shown in the accompanying drawing, in which

Fig. 1 shows the magazine in its folded, out of action position,

Fig. 2 shows the magazine in its firing position.

The magazine, which cooperates with the bolt is held in correct positions by a sleeve 12, in which the upper part of the magazine is introduced as far as its lateral abutment 1 allows this. The sleeve 12, is pivoted, by means of a pin 11, on the fore part of the breech casing.

On the fore wall of the sleeve 12, is arranged a spring controlled magazine-catch 2, the head of which must be pushed from the magazine, when the latter should be released.

On the rear wall of the sleeve 12, is pivoted another spring controlled lever 20, capable to turn at about 180° around its pin.

In the firing position of the magazine as shown by Fig. 2, the lever 20 is automatically folded close to the sleeve 12 and its tooth 3 engages a spring controlled lever 5 pivoted in the foremost end of the trigger guard 10.

When the operator wants to fold the magazine into the forearm of the gun, he depresses the rear arm of the lever 5, thus disengaging the folding sleeve 12.

Subsequently, when the operator turns the magazine and sleeve 12 forward, about pivot 11 of the sleeve 12, the lever 20 is automatically rotated by its spring in counter-clockwise direction (Fig. 1), so that the free end of lever 20 moves toward the fore-end of the trigger-guard. Thus that part of the opening in the shaft, which would otherwise, in the folded position of the magazine, remain open and exposed behind the magazine (Fig. 1) is gradually covered. When the magazine is fully swung into the forearm of the weapon, another tooth 22 of the lever 20 engages the front edge of the trigger-guard, thus

locking the magazine and its sleeve 12 in their folded, out of action position (Fig. 1).

Having now particularly described and ascertained the nature of their said invention and in what manner the same is to be performed, they declared that what they claim is:

1. A firearm comprising a barrel stock, a casing connected thereto, a sleeve adapted to receive a cartridge magazine, said sleeve being pivoted at its fore-part to said casing and adapted to swing through an angle of approximately 90° with respect to said casing, said stock having a cavity in front of said sleeve adapted to receive and conceal said sleeve; said casing being provided with an opening into which said sleeve is adapted to swing to place the magazine contained therein in firing position, a cover carried by and movable cojointly with said sleeve, said cover being pivoted to the rear part of said sleeve

15 and adapted to swing through an angle of approximately 180° with respect to said sleeve, whereby, when said sleeve is inserted in the cavity in said stock, and said cover is swung out with respect to said sleeve the said cover closes said opening in said casing.

2. The device claimed in claim 1, in which said cover is collapsed against the rear wall of said sleeve when the latter is inserted in the opening in said casing, and spring means associated with 20 said cover, said spring means urging said cover away from said sleeve and into position to close the said opening in the casing.

3. The device claimed in claim 1, in which said cover is collapsed against the rear wall of said sleeve when the latter is inserted in the opening in said casing, and spring means associated with 35 said cover, said spring means urging said cover away from said sleeve and into position to close the said opening in the casing, locking means disposed on said cover in proximity to its pivot, cooperating means on said casing adapted to engage said locking means when said sleeve is inserted in the opening in said casing.

4. The device claimed in claim 1, in which said 45 cover is collapsed against the rear wall of said sleeve when the latter is inserted in the opening in said casing, and spring means associated with said cover, said spring means urging said cover away from said sleeve and into position to close the said opening in the casing, cooperating 50 means on said casing, and fastening means disposed at the free end of said cover, said fastening means being adapted to engage said cooperating means when said sleeve is inserted in the cavity in said stock.

5. A firearm comprising a barrel stock, a casing connected thereto, a sleeve adapted to receive a cartridge magazine, said sleeve being pivoted at its fore-part to said casing and adapted to swing through an angle of approximately 90°, said stock having a cavity in front of said sleeve adapted to receive and conceal said sleeve; said casing being provided with an opening into which said sleeve is adapted to swing to place the magazine contained therein in firing position, a cover pivoted to the rear part of said sleeve and adapted to swing through an angle of approximately 180° with respect to said sleeve, said cover being collapsed against the rear wall of said sleeve when the latter is inserted in the opening in said casing, and spring means associated with said cover, said spring means urging said cover away from said sleeve and into position to close the said opening in the casing, and a locking tooth disposed on said cover in proximity to its pivot, a spring controlled lever on said casing, a cooperating tooth on said lever adapted to engage said locking tooth to lock said sleeve when the same is inserted in the opening in said casing, in firing position of the magazine, whereby, when said sleeve is inserted in the opening of said casing, undesirable free vertical movement of the sleeve relative to the firearm is eliminated, said lever being adapted to be operated by hand to release said sleeve from its locked position.

6. A firearm comprising a barrel stock, a casing connected thereto, a sleeve adapted to receive a cartridge magazine, said sleeve being piv-

oted at its fore-part to said casing and adapted to swing through an angle of approximately 90°, said stock having a cavity in front of said sleeve adapted to receive and conceal said sleeve; said casing being provided with an opening into which said sleeve is adapted to swing to place the magazine contained therein in firing position, a cover pivoted to the rear part of said sleeve and adapted to swing through an angle of approximately 180° with respect to said sleeve, said cover being collapsed against the rear wall of said sleeve when the latter is inserted in the opening in said casing, and spring means associated with said cover, said spring means urging said cover away from said sleeve and into position to close the said opening in the casing, first locking means disposed on said cover in proximity to its pivot, a spring controlled lever on said casing, first cooperating means on said lever adapted to engage said first locking means to lock said sleeve when the same is inserted in the opening in said casing, in firing position of the magazine, second locking means disposed at the free end of said cover and second cooperating means provided on said casing, said second locking means being adapted to engage the second cooperating means on said casing when said sleeve is inserted in the cavity in said stock, said lever being manually operable to actuate said first cooperating means.
